CANDY PACKAGE

Application filed November 4, 1929. Serial No. 404,746.

This invention relates to packaging of confectionery, having for its prime object the displaying of a plurality of pieces of candy so that the candy will retain its original dimensions and may be readily vended. Candy having a viscous texture has always proved very difficult to handle, and particularly is this true where it is desired to have the same retain a particular size or shape.

10 A very attractive confection can be made in the form of a plurality of pieces wrapped in a single tube of cellophane or glassine paper, the intersection between the pieces being crimped and secured so that each space 15 between the crimping forms a compartment filled with confection.

Another object is to form a confection that may be readily vended in the form of links which may each be detached in turn without 20 disturbing the main body of the confection.

Other objects will be described in the specification and disclosed in the drawing forming a part of this application.

In the drawing:

25 Figure 1 is an elevation showing the piece of confection ready for vending;

Figure 2 is an elevation showing the first step in the process of forming the links;

Figure 3 is an enlarged detail with part 30 broken away showing the hook formed at the top; and

Figure 4 is an elevation of the empty casing with indicia for tying thereon.

Referring to the drawing, in which like 35 parts are designated by similar numerals:

Numerical 4 designates a hook secured to a display rack 5, or other surface, by means of screws 6. A tube 7 of cellophane or glassine paper is filled with confection, in this case a mixture of ground nuts and chocolate which becomes a viscous mass, the bottom 8 of the tube 7 having first been securely closed by string 9, and the top 8' being crimped and secured after the tube 7 is filled. A point 40 10 intermediate the ends 11 and 12 is selected and the same crimped and tied at two points 13 and 14. This forces the viscous material above and below this point. A point 15 is selected between the points 10 and 8' and 45 50 same is crimped and tied by the use of string

9. This operation is repeated at a point 16 intermediate the points 14 and 8. The portions of the tube 7 between the crimpings form links 17. A portion of the tube 7 is allowed to extend beyond the top 8' and bottom 8 so that the same may be permitted to form loops 18 and 19, the loose ends 20 and 21 being secured at 22 and 23, and the loops 18 and 19 forming supporting means or lifting means, depending upon which end is uppermost.

It is obvious that by suspending the links 17 of viscous material, a novel method of displaying and vending the candy is produced. The links 17 may be snapped or broken off 65 as needed at the point of the crimping, and at the same time, by suspending them in the form of a pendulum, each succeeding link will tend to retain the link above in its proper shape, the cellophane casing preventing 70 undue stretching of the link. By having double bindings, as shown in 13 and 14, the links may be readily detached without exposing the contents of the link above to the atmosphere.

75 I found that by vending candy in this manner, sales are greatly increased, and that I have solved a problem in connection with the vending of candy of a viscous material.

I wish it understood, however, that I do 80 not limit myself to candy having viscous characteristics, as I have found that the same method of vending may be readily applied to candy not having this characteristic.

Having thus described my invention, what 85 I claim is:

A package for confections comprising: a tube divided into elongated sections filled with confectionery, the parts of the tube between sections being crimped to form a neck 90 containing no confectionery, each neck being tied at its opposite ends close to the adjacent sections to permit severing the neck between said ends without untying the adjacent sections, the extreme opposite ends of the tubes 95 being tied to close the end sections and being bent to form loops by which the tube and its contents may be suspended.

In testimony whereof I affix my signature. 100
CHARLES C. CHASE.
